United States Patent Office

Des. 208,173
Patented July 25, 1967

208,173

COMBINED SPOOL OF TYPEWRITER RIBBON AND PACKAGE THEREFOR OR SIMILAR ARTICLE

Delmar J. Lasher and Donald C. Roller, Lexington, Ky.,
assignors to International Business Machines Corpora-
tion, Armonk, N.Y., a corporation of New York

Filed Oct. 22, 1965, Ser. No. 37,744

Term of patent 14 years

(Cl. D58—11)

FIG. 2

FIG. 3

FIG. 1

FIG. 4

FIG. 5

FIG. 6

FIG. 1 is a front elevational view of a combined spool of typewriter ribbon and package therefor or similar article, showing our new design;

FIG. 2 is a top plan view;

FIG. 3 is a left side elevational view;

FIG. 4 is a right side elevational view;

FIG. 5 is a bottom plan view; and

FIG. 6 is a rear elevational view thereof.

We claim:

The ornamental design for a combined spool of type-
writer ribbon and package therefor or similar article, as
shown and described.
